UNITED STATES PATENT OFFICE.

EDWIN V. BABBITT, OF FAIRHAVEN, MASSACHUSETTS.

DESIGN FOR A TOY SAILOR.

Application filed June 8, 1926. Serial No. 17,987. Term of patent 3½ years.

To all whom it may concern:

Be it known that I, EDWIN V. BABBITT, a citizen of the United States, residing at Fairhaven, in the county of Bristol and State of Massachusetts, have invented a new, original, and ornamental Design for a Toy Sailor, of which the following is a specification, reference being had to the accompanying drawing, forming a part thereof.

In the drawing, the figure is a perspective view of a toy sailor showing my new design.

I claim:

The ornamental design for a toy sailor substantially as shown.

EDWIN V. BABBITT.
